NEEDLE THREADER

Carl E. Carlsen, 867 3rd Ave., New York, N.Y.

Filed June 13, 1961, Ser. No. 65,579

Term of patent 14 years

(Cl. D3—19)

FIGURE 1 is a plan view of a needle threader, showing my new design, the side opposite thereto being a mirror image thereof, and

I claim:

The ornamental design for a needle threader, as shown and described.
